UNITED STATES PATENT OFFICE.

MICHAEL J. POWER, OF NEKOOSA, WISCONSIN.

WRAPPING-MACHINE.

1,026,049.

Specification of Letters Patent. Patented May 14, 1912.

Application filed June 19, 1911. Serial No. 634,122.

To all whom it may concern:

Be it known that I, MICHAEL J. POWER, residing at Nekoosa, in the county of Wood and State of Wisconsin, have invented certain new and useful Improvements in Wrapping-Machines, of which the following is a specification.

My invention relates to wrapping machines, particularly to machines adapted for wrapping paper rolls before shipment from paper mills.

Paper rolls in paper mills are usually wrapped before shipment by winding paper around the end sections of the rolls, then folding in the over-hanging ends of the wrappings, and then applying headers to the folded ends to hold these wrappings or caps in place. Heretofore the greater part of such wrapping has been done by hand, which, of course, is a very costly procedure, and the broad object of my invention is to provide a machine which will automatically wrap the paper rolls and deliver them ready for shipment.

More in detail, the objects of the invention are to provide a machine into which the rolls are received from the mill and paper lengths automatically wound about the ends and then automatically folded in, and then caps automatically pasted over the folded-in ends; to provide improved mechanism for automatically feeding in the wrapping paper and cutting it into proper lengths; to provide improved means for applying pasting material to the wrapping lengths; to provide improved means for automatically folding in and together the over-hanging ends of the wrapping lengths; to provide improved means for simultaneously cutting paper heads from automatically fed supply paper and for pasting these heads against the folded-in sections of the wrapping caps; and to provide improved means for discharging the wrapped rolls from the machine; and in general to provide an all-around efficient machine and one of simple construction for quickly and rapidly and entirely automatically wrapping paper rolls.

My invention will be clearly understood by reference to the accompanying drawings, in which—

Figure 1 is a plan view; Fig. 2 is a side view looking from the left of Fig. 1; Fig. 3 is a side view looking from the right of Fig. 1; Fig. 4 is a front elevational view; Fig.

5 is a more or less diagrammatic view from the right of Fig. 1 with parts removed to show more clearly the operation of more internal parts; Fig. 6 is a plan view with parts removed and parts of the heading mechanism shown in section; Fig. 7 is a front elevational view with parts removed and parts of the heading mechanism shown in section; Fig. 8 is a detached view showing cam arrangement controlling certain detent mechanism; Fig. 9 is a view taken substantially on plane 9—9, Fig. 6, showing cam mechanism for controlling the cutting blade; and Fig. 10 is a view taken substantially from plane 10—10, Fig. 6, showing cam mechanism for controlling paste applying apparatus.

The various operating parts of the machine are mounted on supporting frame-work designated in general A. Above this frame-work is a run-way or chute 10 along which the paper rolls ^r to be wrapped are fed to the machine. Extending transversely across the supporting frame of the machine is a shaft 11 journaled in the standards 12 and 13 carrying at its outer end a belt wheel 14 (see Fig. 1). Between the standards the shaft also carries two conveyer plates 15 each formed by cutting semi-circular portions out of a circular disk to leave conveyer wings 15^a and pockets 15^b. As shown, three such wings and pockets are provided for each plate. Directly below the shaft 11 are the carrier rolls 16 and 17 mounted on shafts 18 and 19 respectively suitably journaled on the supporting frame A of the bases of the standards 12 and 13 and at the opposite sides thereof. At one end shaft 19 carries a belt pulley 20, and the opposite end of this shaft carries a sprocket wheel 21 about which engages a chain 22 which passes also about a sprocket wheel 23 on shaft 18. Shaft 18 carries at its ends the belt wheels 24 and 25 respectively, belts 26 and 27 connecting these belt wheels with belt pinions 28 and 29 on shafts 30 and 31 respectively journaled in bearing boxes 32 and 33 mounted respectively on the sides of standards 12 and 13, as best shown in Figs. 2 and 3. At the inner ends of shafts 30 and 31 respectively are mounted hubs 34 and 35 carrying the star-shaped folding members 36 and 37 respectively, the arms of these star wheels being of substantially semi-spherical form, as shown. The shaft 11 at its right end (Fig. 3) carries a

wheel 38 having transverse notches 39 in its rim spaced 120 degrees apart.

In lugs 40, 41 extending from the standard 13 below the wheel 38 a detent pin 42 is vertically reciprocable and is surrounded by a compression spring 42^a engaging between the lug 41 and the abutment pin 43 on the detent pin. The lower end of the detent pin is pivoted to one end of a bell crank lever 44 pivoted at its elbow at 45 to the standard 13 and having the end of its other arm pivoted to a cam rod 46 having at its rear end the head 47 provided with a longitudinal slot 48, this slot receiving the end of the 15 shaft 49 extending transversely across the machine below the bed plate *a* and suitably journaled at opposite sides from said bed plate. The cam rod head 47 also pivots a cam roller 50 at one end of the slot adapted 20 to be engaged by the cam tooth 51 extending from hub 52 secured to the outer end of the shaft 49. With this arrangement, as the shaft 49 rotates, the tooth 51 and roller 50 will coöperate once during each revolution to 25 carry the cam rod 46 rearwardly to cause rotation of the bell crank lever 44, and withdrawal of the end of detent pin 42 from one of the notches 39 of detent wheel 38, and immediately after the tooth 51 has 30 passed the roller the parts will be free to allow the spring 42 to press the detent pin against the detent wheel ready to enter the next notch 39 to again lock the shaft 11 and the conveyer members 15 against rotation, 35 each angular advance of the members 15 resulting in the conveying of a paper roll from the chute 10 into position on the rollers 16 and 17.

The machine is intended to wrap paper 40 lengths about the ends of the rolls, and accordingly, paper feed mechanism is provided for supplying paper lengths to each end of the roll when in place on the rollers 16 and 17. At the rear end of each side of 45 the machine there are standards 53 and 53', these standards forming bearings for a shaft 54 for accommodating the wrapping paper supply rolls 55, 55', one for each end of the rolls wrapped. In front of the standards 50 53 and 53' the bed plate *a* supports standards 56 and 56' at opposite sides, and in front of these standards are similar standards 57 and 57'. At the lower ends of the standards 56 and 56' a shaft 58 is journaled 55 mounting the feed rollers 59 and 59' at opposite sides, and above these rollers are the top rollers 60 and 60' on shaft 61 also journaled in these standards 56 and 56'. In the standards 57 and 57' are journaled the upper and lower shafts 62 and 63 bearing the lower and upper rollers 64, 64' and 65, 65' respectively. Between the standards 53, 53' and 56, 56' the bed plate carries bearing blocks 66 and 66' at opposite sides journaling the shaft 67 carrying the guide roll-

ers 68 and 68' respectively at opposite sides. The paper from the roll 55 passes downwardly below the roller 68, then between the rollers 59 and 60, and then between the rollers 64 and 65, 70 while the paper from the opposite roll 55' passes similarly through the rollers at that side of the machine. On the right end of shafts 58 and 62 are mounted sprocket wheels 69 and 70 respectively with which an endless driving chain 71 meshes. This chain also passes over a guide sprocket wheel 72 suitably pivoted on the bearing standard 57, as best shown in Fig. 3. The chain also passes over a sprocket wheel 73 at the end 80 of a shaft 74 journaled at its ends in extensions 75 and 75' on bearing standards 56 and 56', these shafts carrying paste applying rollers 76 and 76' which engage respectively with the upper feed rolls 60 and 60'. 85 The paste wheels dip into a suitable paste containing pan 77 and carry paste to the rollers 60 and 61 which apply it to the paper coming from the supply rolls 55 and 55'. The shaft 58 also carries a pinion 78 meshing with a gear 79 mounted in a suitable bearing on the bed plate *A*, this gear wheel being intermittently rotated by the gear wheel 80 mounted on the shaft 49, as best shown in Fig. 3, this gear wheel having 90 teeth over only substantially one-half its periphery. During rotation of the gear wheel 79 by the wheel 80 the chain 71 will be advanced and the various members connected therewith rotated to cause predetermined lengths of wrapping paper to be fed forwardly to be used for wrapping about the ends of the rolls on the rollers 16 and 17. 95

Between the paper feed mechanism and the rolls 16 and 17 knife mechanism is 105 interposed for cutting off the lengths of wrapping paper. This knife mechanism is mounted on a beam 81 extending transversely across the bed plate *A* and carrying at its opposite ends upright bars 82, 83 and 82', 83' respectively (Figs. 2 and 3). Links 84 and 84' hang from pins 85 and 85' between the respective uprights, and the lower ends of these links suspend the knife bar 86. This knife bar has a laterally extending arm 87 to which is pivoted the upper end of a depending link 88 pivoted at its lower end to the arm 89 secured to the transverse shaft 90 journaled in the bearing block 91 depending from the bed plate *A*. (See Figs. 3 and 6). The inner end of this shaft carries an arm 92 at an angle with the arm 89 and pivoted at its end to a cam rod 93. As best shown in Fig. 9, the rear end 94 of the cam rod 93 is longitudinally slotted and receives the hub 95 mounted on shaft 49. This hub has a flange 96 having a cam groove 97 in its side, and on cam arm 93 is pivoted a cam roller 98 for engaging in this groove. In the position best 110 115 120 125 130

shown in Fig. 9 the cam roller 98 engages in the circular part of groove 97, and the cam rod 93 is held forwardly to keep the arm 89 raised to thereby swing the knife blade on its links upwardly away from the paper passing over the beam 81. Upon rotation of the shaft 49 the roller will be engaged by the groove 97 to cause rearward movement of rod 93 and downward movement of the knife bar to sever the wrapping paper bands fed from rolls 55 and 55'. There are also provided at each side of the machine in advance of the rolls 16 and 17 paste receptacles 99 and 99' for applying paste to the trailing ends of the wrapping paper sections so that when the ends of these sections are finally folded over the ends will be pasted and prevented from unwrapping. For each paste receptacle valve mechanism 100 is provided which, when raised, will cause paste to flow onto the paper. Each valve mechanism connects by means of a rod 101 with a bell crank lever 102, from which extends a cam rod 103 having a slotted rear end 104. This slotted end engages a hub 105 on shaft 49, and each hub carries a cam flange having a cam tooth 106 for co-operation with a cam roller 107 on the cam rod 103.

The mechanism thus far described is instrumental in applying the wrapping ends to the rolls, and the operation thereof can be readily understood. Referring particularly to Fig. 3, the wrapping operation on a roll r' is just being completed. The carrier members 15 are held by engagement of the detent pin 42 with the wheel 38. The teeth on wheel 80 have just left the wheel 79 after a feed operation of the paper feed mechanism, and the cam groove 97 and cam roller 98 have co-operated to cause the knife to sever the wrapping paper bands. Also, substantially immediately after the knife has been lowered the cam teeth 106 have co-operated with the cam rollers 107 to cause discharge of paste from the receptacles 99 and 99' to the trailing ends of the paper bands which are to form the end wrappings for the roll r' in place on rollers 16 and 17. In the positions shown, therefore, the end wrapping operation of the roll r' has just been completed, and the roll is ready to be discharged from the rolls 16 and 17 into the heading mechanism. Accordingly, as wheel 80 continues to revolve from the position shown, particularly in Fig. 3, the cam tooth 51 will strike cam roller 50 on cam lever 46, and the detent pin 42 will be pulled down to release the wheel 38 and thereby the members 15, and these members are then driven to discharge the roll r' forwardly from the rolls 16 and 17 and into the heading mechanism and to feed to the rolls 16 and 17 the next roll r^2 .

During travel of the roll r^2 toward the rolls 16 and 17 the teeth on wheel 80 are again approaching the gear wheel 79, and the teeth will have been in engagement for a time before the roll r^2 reaches the rolls 16 and 17, so that the wrapping paper feed mechanism will have been actuated a sufficient length of time to carry paper forwardly over the roll 17 and into position to be engaged between the roll r^2 and roll 17 when the roll r^2 finally comes to rest on the rolls 16 and 17. The wrapping paper bands having had paste applied thereto will then of course stick to the roll r^2 , and the peripheral speed of the rolls 16 and 17 being adjusted to be substantially the same as the speed given the paper by the feed mechanism, the paper will be wound about the ends of the roll r^2 , and as soon as enough paper has been fed the feed mechanism stops and the knife immediately severs the paper and paste is applied to the ends of the severed bands, and these pasted ends are then finally wound against the roll r^2 . Of course, during the rotation of the roll r^2 the folding members 36 and 37 are rotated, and the over-hanging ends of the paper bands are folded together, and the paste applied to the bands by the mechanisms 99 and 99' becomes effective to secure the folded bands to prevent unwrapping thereof. To assist in guiding and holding the paper in place on the rolls during the wrapping operation, arms 108 and 108' extend from shaft 11 and pivot rollers 109 and 109' between their ends which engage the ends of the rolls to be wrapped, and due to their weight keep the wrapping paper snugly in place and prevent unwrapping thereof. The rolls are also guided on their way from the chute to the rollers 16 and 17 by arms 110 extending downwardly from the chute structure. The shaft 49 controlling the various cam mechanisms and the operation of the paper feed mechanism is driven by means of a sprocket chain 111 passing over the sprocket wheel 112 on said shaft, and the sprocket wheel 113 on the shaft 114. This shaft carries a gear 115 meshing with a driving pinion 116 on the shaft 117, which shaft carries the driving pulley 118.

I shall now describe the heading mechanism of the machine. The shaft 114, just referred to above, extends transversely across the front of the machine and is journaled in bearing standards 119, 119' and 120, and carries various mechanisms and cam mechanisms for controlling the operation of the heading mechanism. As best shown in Fig. 5, the supporting frame of the machine in front of the rolls 16 and 17 carries support bars 121, 121' for receiving the rolls after they leave the grappling rolls 117, and an incline 122 leads from the roll 16 to the bars 121. These bars support transverse

bars 123 and 123' and 124, which finally receive the roll to be headed and prevented from movement during the heading operation. At each side of this space into which the rolls are delivered to be headed heading mechanism is provided, the heading mechanism on one side being exactly the same both as to construction and operation as the heading mechanism at the opposite side, and only one such heading mechanism need therefore be described. Referring to Figs. 4 and 6, a bearing standard 125 slidably supports a sleeve 126 terminating in a circular head 127 at its inner end, the sleeve being bored to slidably receive a rod 128 having at its inner end a disk 129 provided with a center pin 130. Extending inwardly from the head 127 is an annular blade 131 which co-operates with an annular plate 132, this plate being supported at the inner ends of studs 133 extending slidably through the head 127, compression springs 134 encircling the studs between the shearing plate and the head. Inwardly of the bearing standard 125 a standard 135 has the annular head or sleeve 136 carrying at its outer edge the annular shearing blade or ring 137.

As will be explained more in detail later, the paper from which the heading blanks are cut is fed downwardly between the annular plate 132 and the shearing ring 137, so that when the head 127 is moved inwardly the paper will be clamped between the plate 132 and the shearing ring 137 by force of springs 134, and the blade 131 will then pass through the plate 132 and its edge will co-operate with the inner cutting edge of the ring 137 to cut a circular heading blank from the paper, which heading blank is received on the pin 130 and is then carried, upon further inward movement of the rod 128, against the end of the roll by the head 129, paste having continuously been applied to the paper. The operation of the shearing head 127 and the placing head 129 is controlled by levers 138 and 139 co-operating with cams 140 and 141 respectively mounted on the shaft 114. The lever 138 is pivoted at an intermediate point 142 to the machine frame, and its inner end is pivoted to the outer end of sleeve 126 at 143, while the outer end carries a cam block 144 which co-operates with the cam 140, this cam having the cam slot 140'. Lever 139 is pivoted at an intermediate point to the machine frame at 145, its rear end being pivoted at 146 to the outer end of rod 128, and the outer end having a cam roller 147 co-operating with the cam 141, which has the laterally extending cam ridge 141'. In the normal position shown in Fig. 6, the cam mechanisms are in such position that the sleeves 126 and rods 128 are in their outer positions with the heads 129 resting against the inner face of the heads 127. Referring to Figs.

3, 4 and 7, a leaf spring 148 is provided at each side of the machine and secured at its outer end to an extension 149 from the standard 119, and its other end is bifurcated to receive the corresponding rod 128 and presses inwardly against the outer end of the sleeve 126, tending to move the sleeve and its head 127 inwardly. However, such inward movement is normally prevented by the engagement of cam block 144 with the high part of the cam 140. As the shaft 114 is rotated the levers 138 and 139 are also rotated about their pivots. The cam blocks 144 first drop into cam grooves 140' to allow the springs 148 to move the heads 127 inwardly to cause the shearing of header blanks from the supply paper, and immediately thereafter the cam rollers 147 engage with the cam ridges 141', and the rods 128 are moved inwardly so that the sheared blanks are carried by heads 129 against the folded ends of the rolls fed into the heading field. This position of the parts is shown in Figs. 4 and 7.

Coming now to the paper feed mechanism for the header blanks, a table 150 is provided at each side of the machine adjacent the heading field. On each table a standard 151 carries a rod 152 for mounting a supply paper roll 153. In front of this standard is a bearing bracket 154 carrying at its front upper and lower feed rolls 155 and 156 respectively, and at the outside of the top roll 155 carrying a paste applying roll 157, this paste roll dipping into a suitable paste containing pan 158. At the outside of the standard 151 bearing blocks 159 journal a guide roll 160. The paper passes from the roll about the guide roller 160, then between the upper and lower rolls 155 and 156, and thence downwardly between the annular plate 132 and shearing ring 137. The paste roll 157 engages the upper roll 155 to apply paste thereto, and this upper roll in turn applies the paste to the paper before it passes between the shearing edges to have the blank heads cut therefrom. The feed and paste rolls are suitably driven by means of a chain 161 passing about a sprocket wheel 162 at the inner end of a shaft 163 journaled in the standard 135. This shaft at its front end carries a pinion 163' which meshes with a gear 164 mounted on shaft 114. At its rear end this shaft 163 also carries a gear 165 meshing with a gear 166 on the inner end of shaft 167 which is parallel with the shaft 163 and which carries feed rolls 168 and 169 between which and the outer face of standard 135 the paper is passed after it leaves the shearing mechanism, the rolls by their engagement with this paper serving to keep the paper stretched across the shearing edges during the shearing operation. The paper feed mechanism should, of course, be operated

130

intermittently and only at times when the heads 127 and 129 are in their outermost position. Accordingly, clutch mechanism is provided for automatically cutting in the paper feed mechanisms during this time. The gear wheels 164 for transmitting movement to the paper feed mechanisms from shaft 114 are mounted on hubs 170 whose inner ends carry conical flanges 171 for co-operating with conical heads 172 carried on sleeves 173 slideable on shaft 114. Pivoted to each sleeve is the bifurcated ends 174 of a shaft lever 175, these levers being pivoted at an intermediate point to a cross bar 176 secured to the standards 135. By referring to Fig. 4, the left lever 175 has connected to its lower end a link 177 which pivots at its other end about the lower end of a supplemental lever 178 pivoted at an intermediate point to the cross bar 176 and carrying at its upper end a cam roller 179 for co-operating with the cam disk 180 on shaft 114. A link 181 connects the upper end of the supplemental lever 178 with the lower end of the right lever 175, so that upon co-operation of the cam roller 179 with the cam ridge 180 both levers 175 will be swung to carry their clutch heads 173 into frictional engagement with the clutch pockets 171 whereupon hubs 170 will be rotated and the paper feed mechanisms for the heading blanks actuated. The paper having had paste applied thereto, the blanks carried inwardly by the heads 129 will be secured to the ends of the rolls and against the folds of the wrappers, and the wrapping operation is completed. After such application of the heads the sleeves 126 and rods 128 are restored to their normal positions by engagement of the cams 140 and 141 with the levers 138 and 139. As before stated, the rolls are held in place on the bars 121 by the ridges 123 and 124, and I therefore provide means for ejecting a roll from the machine after the paper heads have been applied to the ends thereof. As best shown in Figs. 5, 6 and 7, a shaft 182 is journaled in standards 135 and carries two ejecting arms 183. Between these arms this shaft also carries an arm 184 with which is connected a slotted link 185 receiving the shaft 114. On this link there is also a cam roller 186 adapted for engagement with a cam tooth 187 on the hub 188 mounted on shaft 114. During heading operation the ejecting arms 183 are dropped below the roll between the head applying mechanisms, and immediately after the heads have been applied thereto the cam tooth 147 engages the cam roller 186 to move the link 185 inwardly to cause rotation of shaft 182 and to cause the ejector arms 183 to engage with the roll and to force it out of the machine to the front ends of the supporting bars 121 where it can be conveniently removed.

I thus provide a wrapping machine which is entirely automatic in its operation and to which the paper rolls can be fed and from which they are automatically discharged after the wrapping operations have been all carried out automatically.

I do not, of course, desire to be limited to the precise construction, arrangement and operation which I have shown and described, as changes and modifications are of course possible which would still come within the scope of the invention, and I therefore claim the following:

1. In a wrapping machine, the combination of feed mechanism for feeding rolls to be wrapped, rotatable conveyer mechanism having pockets for receiving the rolls from the feed mechanism, supporting drums for receiving rolls from the conveyer mechanism, means for rotating said drums to cause rotation of the rolls supported thereon, means for feeding paper bands between said roll and the supporting drums to be wrapped about the ends of said roll upon rotation thereof by said drums, rotatable folding members mounted adjacent said drums to engage with the overhanging ends of the bands to fold said ends against the roll ends, and means for securing paper disks to said folded ends. 95

2. In a wrapping machine, the combination of feed mechanism for feeding rolls to be wrapped, rotatable conveyer mechanism having pockets for receiving said rolls one by one from the feed mechanism, drums for receiving the paper rolls one by one from said conveyer mechanism, means for rotating said drums to cause rotation of the roll thereon, means for feeding wrapping bands over said drums to be received between said drums and the roll thereon and to be wrapped about the ends of said roll upon rotation thereof by said drums, rotatable disks mounted adjacent the ends of said drums and having semi-spherical projections for engaging with the overhanging ends of said bands as said bands are wrapped about the roll ends whereby said overhanging ends are folded together against the roll ends, and means for applying heads against said folded ends. 110 105

3. In a wrapping machine, the combination of feed mechanism for feeding rolls to be wrapped, rotatable conveyer mechanism having pockets for receiving the rolls from the feed mechanism, supporting drums for receiving rolls from the conveyer mechanism, means for rotating said drums to cause rotation of the rolls supported thereon, means for feeding paper bands between said roll and the supporting drums to be wrapped about the ends of said roll upon rotation thereof by said drums, rotatable folding members mounted adjacent said drums to engage with the overhanging ends 130 125 120

of the bands to fold said ends against the roll ends, heading mechanism, said conveyer mechanism acting to convey a roll to the heading mechanism after application of the 5 end wrapping bands thereto, laterally reciprocable heads, means for providing heading blanks on said heads, and means for moving said heads toward the ends of the roll and the heading mechanism to cause 10 application of the supported heading blanks over the folds of the wrapping bands on said roll.

4. In a wrapping machine, the combination of feed mechanism for feeding rolls to 15 be wrapped, rotatable conveyer mechanism having pockets for receiving the rolls from the feed mechanism, supporting drums for receiving rolls from the conveyer mechanism, means for rotating said drums to cause 20 rotation of the rolls supported thereon, means for feeding paper bands between said roll and the supporting drums to be wrapped about the ends of said roll upon rotation thereof by said drums, rotatable folding 25 members mounted adjacent said drums to engage with the overhanging ends of the bands to fold said ends against the roll ends, heading mechanism, said conveyer mechanism acting to convey a roll to the 30 heading mechanism after application of the end wrapping bands thereto, laterally reciprocable heads, means for providing heading blanks on said heads, means for moving said heads toward the ends of the 35 roll and the heading mechanism to cause application of the supported heading blanks over the folds of the wrapping bands on said roll, and means for automatically discharging 40 the roll from said heading mechanism.

5. In a wrapping machine, the combination of supporting framework, rotatable conveyer mechanism mounted on said framework, peripheral pockets, feed mechanism for feeding to said pockets rolls to be 45 wrapped, a pair of drums journaled on said framework for receiving a roll from the conveyer mechanism, means for causing rotation of said drums and of the roll carried thereby, two sets of wrapping paper feed 50 mechanism mounted on said supporting structure and adapted when operated to feed paper bands toward the ends of said drums to be received between said drums and the roll thereon and to be carried by the rotation of said drums and roll to be wrapped 55 about the roll ends and to overhang the roll ends, rotatable disks mounted adjacent the roll ends and having semi-spherical projections for engaging the overhanging ends of 60 the wrapping bands to fold said ends against the roll ends, means for applying paste to the wrapping bands for application thereof to the roll, heading mechanism, means controlled by said conveyer mechanism for automatically transferring a roll from the 65

drums to the heading mechanism, means forming part of the heading mechanism for pasting paper heads against the folds of the wrapping bands on the roll, and means for automatically discharging the roll from the 70 heading mechanism.

6. In a wrapping machine, the combination of supporting framework, a conveyer frame having peripheral pockets, feed mechanism for feeding to said pockets rolls to be wrapped, drums rotatably mounted on said framework below said conveyer frame for receiving rolls therefrom and means for rotating said drum and thereby the roll thereon, wrapping paper feed mechanism, 80 means for causing intermittent operation of said feed mechanism to feed paper bands to said drum to be carried between said drums and rolled thereon and to be wrapped about the ends of said roll, means for applying paste to said bands before application thereof to the roll, folding members mounted over the drums and having semi-spherical projections for engaging with the overhanging ends of the wrapping bands to fold said ends 85 against the roll ends, heading mechanism, laterally reciprocable heads for said heading mechanism, means for automatically transferring a roll from the drums to the heading mechanism into position between said 90 heads, means for feeding paper in front of said heads, cutting mechanism on said heads, means for actuating said cutting mechanism to cut heading disks from said paper, means for applying paste to said paper, and 95 means for causing inward movement of said heads to carry the disks against the folded ends on said roll between said head.

7. In a wrapping machine, the combination of supporting framework, a conveyer frame journaled on said framework and having peripheral pockets, feed mechanism for feeding to said pockets rolls to be wrapped, drums journaled on said framework below said conveyer frame for receiving a roll from said conveyer frame, means for rotating said drums and thereby the roll thereon, feed mechanism on said framework and paper supply therefor, means for intermittently operating said feed mechanisms to 105 feed paper bands toward the ends of the roll on the drums, knife mechanism interposed between said feed mechanisms and the drums for cutting said wrapping paper into sections, the sections being received between 110 the drums and roll thereon to be wrapped about the roll ends upon rotation thereof, folding disks journaled over the drum ends and having semi-spherical projections for engaging the wrapping paper sections as 115 they are wound about the roll to fold the overhanging ends of said wrapping sections against the roll ends, heading mechanism, 120 detent mechanism for holding the conveyer frame at rest after delivery by said frame 125 130

of a roll to said drums, cam mechanism for releasing the conveyer frame after the wrapping sections have been applied to and folded over the ends of the roll whereby said 5 conveyer frame may be rotated to transfer the roll from the drums to the heading mechanism, and means forming part of the heading mechanism for pasting heading disks against the folds at the end of the 10 roll received by the heading mechanism.

8. In a wrapping machine, the combination of supporting framework, a rotatable conveyer frame, feed mechanism for feeding rolls to be wrapped to the conveyer frame, 15 drums journaled below said conveyer frame for receiving rolls therefrom one by one, means for rotating said drums and roll thereon, paper feed mechanism for feeding paper bands between said drums and roll to be wrapped about the ends of said roll upon 20 rotation thereof, folder members adjacent the ends of said roll, means for causing rotation of said folder members to fold the overhanging sides of said wrapping paper 25 against the roll ends, opposed heads, means for feeding paper past said heads, means for cutting disks from said paper, means for applying paste to said paper, means for conveying between said heads the rolls from 30 said drums, and means for bringing said heads together to cause application to the roll ends of said paper disks.

9. In a wrapping machine, the combination of supporting framework, a pair of drums journaled side by side on said supporting frame, means for feeding paper rolls to be wrapped to said drums, means for rotating said drums and thereby the roll thereon, means for feeding paper wrapping 35 bands between said drums and roll to be wrapped about the ends of said roll, opposed heads, means for transferring a roll from

said drums into position between said heads, means for feeding paper past said heads, knife mechanism for cutting disks out of 45 said paper, means for causing said heads to be brought together to receive the disks and to carry said disks against the wrapped ends of the roll, and means for discharging the 50 roll from the machine.

10. In a wrapping machine, the combination of supporting mechanism for rolls to be wrapped, means for feeding rolls to said supporting mechanism, means for rotating the rolls when on the supporting mechanism, 55 means for feeding paper bands to said roll and wrapping said bands around the roll ends during rotation thereof, rotatable folding members mounted adjacent the roll ends for engaging with the overhanging ends of 60 the bands to fold said bands against the roll ends, and means for securing end disks to said rolls against the folded ends of said bands.

11. In a wrapping machine, the combination of supporting framework, a pair of drums journaled side by side on said supporting framework, means for feeding rolls to be wrapped to said drums, means for rotating said drums and thereby the roll 70 thereon, means for feeding paper wrapping bands between said drums and roll to be wrapped about the ends of said roll, folding members for folding the overhanging ends of said bands against the ends of said roll, 75 and means for securing disks to the roll ends against the folded ends of the bands.

In witness whereof, I hereunto subscribe my name this 6th day of May, A. D., 1911.

MICHAEL J. POWER.
